(57) **CLAIM**

The ornamental design for a cartomizer for a vaporizer, as shown and described.

DESCRIPTION

FIG. 1 is a front perspective view of a cartomizer for a vaporizer with the cartomizer inserted into the battery portion for the vaporizer, the battery portion illustrated in broken lines; FIG. 2 is an exploded front perspective view of the cartomizer of FIG. 1 with the cartomizer removed from the battery portion, the battery portion illustrated in broken lines; FIG. 3 is a top view of the cartomizer of FIG. 1; FIG. 4 is a side view of the cartomizer of FIG. 1; FIG. 5 is a front view of the cartomizer of FIG. 1; FIG. 6 is a rear view of the cartomizer of FIG. 1; and, FIG. 7 is a bottom view of the cartomizer of FIG. 1. The broken lines in the drawings depict environment that forms no part of the claimed design.
